(57) **CLAIM**

The ornamental design for a jeweled frame for a dimmer, as
shown and described.

DESCRIPTION

FIG. 1 is a perspective view of a jeweled frame for a dimmer
showing my new design.

FIG. 2 is a front view thereof; and,

FIG. 3 is a left side view thereof, the right side, top and
bottom views being identical to the left side view.

The rear view forms no part of the design and is omitted.
